UNITED STATES PATENT OFFICE.

ALBERT ERNEST DUNSTAN, OF SUNBURY, ENGLAND.

REFINING LIQUID HYDROCARBONS.

Application filed June 2, 1919. Serial No. 301,359.

To all whom it may concern:

Be it known that I, ALBERT ERNEST DUNSTAN, D. Sc., a subject of the King of Great Britain and Ireland, residing at Meadhurst, 5 Cadbury Road, Sunbury-on-Thames, England, have invented certain new and useful Improvements Relating to Refining Liquid Hydrocarbons, of which the following is a specification.

10 This invention relates to a process of refining benzine, kerosene or other distillates from petroleum, shale oil and the like by the removal therefrom of the sulphur compounds such as organic sulphides, polysulphides and hydro-sulphides they may contain.

This invention particularly relates to the refining of oil for the removal of bad odors, to destroy any coloring matter originally present and to eliminate or prevent development of acid or corrosive products. So far as the causes of these objectionable properties are known, organic compounds of sulfur are chiefly responsible. The precise 25 structure of all the sulfur compounds present in petroleum distillate and the like is not known, but I find that all the sulfur in these oils is amenable to treatment according to this invention.

30 According to the invention the liquid hydrocarbon is subjected to treatment with an alkaline solution of a hypochlorite, whereby the sulphur compounds contained in the liquid hydrocarbon are oxidized and 35 bodies produced that readily pass into and are removed with the lye.

According to the invention, moreover, the treatment is effected in the presence of an excess of alkali.

40 The invention comprises the features which are hereinafter described.

The invention is diagrammatically illustrated in the accompanying drawing.

The invention may be carried into effect 45 in any suitable form of electrolytic apparatus. For example an iron or steel vessel *a* of upstanding cylindrical form may be employed suitably earthed and carbon or graphite anodes *c* may be used, and heat may 50 be applied to the vessel in any suitable or convenient way. The liquid hydrocarbon may be poured into the electrolyte and the electrolysis may proceed while the electrolyte is actively stirred by a stirrer *b*. Heat 55 may be applied to the vessel so that the treatment may take place at the optimum

temperature. I have found a temperature of 120° F. effective.

Any suitable hypochlorite may be used such as sodium hypochlorite with the addition of free alkali.

The presence of free alkali has the effect of preventing corrosion of the vessel, of inhibiting chlorination of hydrocarbons, of stabilizing the hypochlorite and of assisting in the removal of the products of the treatment which result mainly from the oxidation of the organic sulphur compounds originally present in the liquid hydrocarbon treated.

The alkaline solution of a hypochlorite 70 may be produced in an apparatus external to the mixer in which the operation proceeds. In fact, the solution may be prepared by any of the known methods, such as electrolysis of a salt solution in special cells for 75 the production of hypochlorite, by passing liquid chlorine into a solution of an alkali such as caustic soda or milk of lime, or by dissolving bleaching powder in sufficient water to produce a solution of the proper 80 hypochlorite content and alkalinity.

As has been pointed out above the presence of free alkali renders the solution free from ancombined chlorine, and inhibits the chlorination of the hydrocarbon. Liquid hydrocarbons refined according to this invention 85 are chlorine free for all practical purposes.

The oil to be treated should be analyzed so as to discover its sulphur content. For each unit amount of sulphur there should be 90 provided at least one unit amount of oxygen resulting from the decomposition of hypochlorite. The amount of free alkali should at least be of the order of 0.1 per cent concentration. The concentration of the hypochlorite should be at least 0.25 normal. The current density in the electrodes may be from .15 to .40 amperes per square centimeter. The duration of treatment should 95 be determined by test with each individual oil.

In cases where the oxidized sulphur compounds are of high molecular weight and are relatively insoluble in alkali, they may be removed from solution in the refined oil 105 by means of filtration through animal charcoal, dehydrated alumina, fuller's earth or any suitable decolorizing agent.

Before treating hydrocarbons containing hydro-sulphides or mercaptans, the hydrocarbon may be first treated with caustic soda 110 so that it may be substantially deprived of

these bodies before treatment according to the invention and thus the hypochlorite economized.

I claim:

- 5 1. A process for refining liquid hydrocarbons containing sulfur compounds, comprising subjecting said hydrocarbons to treatment with a solution comprising a hypochlorite in concentration at least 0.25 normal and free alkali in concentration at least 0.1 per cent.
- 10 2. A process for refining liquid hydrocarbons containing sulfur compounds, com-

prising subjecting said hydrocarbons to treatment with a solution consisting of a 15 hypochlorite and free alkali without introducing chlorine into the liquid hydrocarbons.

3. A process for refining liquid hydrocarbons containing sulfur compounds, comprising subjecting said hydrocarbons to 20 treatment with an alkaline solution of a hypochlorite in proportion to provide about one unit of oxygen from decomposition of the hypochlorite to each unit of sulfur in the liquid hydrocarbon.

ALBERT ERNEST DUNSTAN.
